(57) **CLAIM**

The ornamental design for an alarm clock, as shown and described.

DESCRIPTION

FIG. 1 is a top, front and right side perspective view of an alarm clock showing our new design;

FIG. 2 is a front elevational view of the alarm clock of FIG. 1;

FIG. 3 is a rear elevational view of the alarm clock of FIG. 1;

FIG. 4 is a left side elevation of the alarm clock;

FIG. 5 is a right side elevation of the alarm clock;

FIG. 6 is a top plan view of the alarm clock; and,

FIG. 7 is a bottom plan view of the alarm clock.

The broken lines of FIGS. 1-7 are for the purpose of illustrating structure of the alarm clock that form no part of the claimed design and that are unclaimed subject matter.
